ADJUSTABLE SUPPORT STRUCTURE

Alvin L. Johnson, Worcester, Mass.

Application January 11, 1946, Serial No. 640,541

7 Claims. (Cl. 38—121)

1

This invention relates to adjustable supports in general and it is the principal object of the invention to provide a support such as a table, chair, lap board, etc., the height of which is readily adjustable.

Several persons of varying heights in a household may wish to use the same table, chair, or ironing board, or the same person may use the same at usual height when doing certain things but will want the table or board at a lower level when doing something else. It is an important object of my invention to provide a table, chair, or any board the height of which can be changed easily by the user merely by depressing a convenient pedal or lever.

It is another object of my invention to control the height of a support by a mechanism readily released to permit lowering thereof but so constructed that it will slip and remain in any desired position when the support is raised.

The present support is carried by two pairs of legs one pair of which is pivoted to one end of the support. The other pair of legs is connected to the support by an improved sliding attachment which acts not only to permit sliding but also frictionally resists too rapid descent of the support when the pedal is released.

It is a more specific object of the invention to connect the bottoms of the aforesaid two pairs of legs by a friction lock releasable by the pedal. Two springs of unequal strengths act on the lock, one normally holding it in locking position but being overpowered by the other spring to move the lock to unlocked position when the pedal is depressed.

It is a more particular part of the invention to locate the lock and parts associated in it in a housing which is so located as to engage the pivot of the legs and thus prevent bending of the control and locking rods when the support is collapsed for storage purposes.

With these and other objects in view which will appear as the description proceeds, my invention resides in the combination and arrangement of parts hereinafter described and set forth.

In the accompanying drawings:

Fig. 1 is a front elevation of the preferred form of my invention, parts being in section,

Fig. 2 is an enlarged vertical section on line 2—2, Fig. 1,

Fig. 3 is a vertical section on line 3—3, Fig. 2,

Fig. 4 is an enlarged vertical section on line 4—4, Fig. 1,

2

Fig. 5 is a plan view looking in the direction of arrow 5, Fig. 1, parts being broken away,

Fig. 6 is a horizontal section on line 6—6, Fig. 1,

Fig. 7 is an enlarged vertical section on line 7—7, Fig. 6,

Fig. 8 is a vertical section on line 8—8, Fig. 7,

Figs. 9 and 10 are diagrammatic side elevations showing the manner of lowering and raising, respectively, the support shown in Fig. 1, and

Fig. 11 shows the preferred form of support collapsed and standing on end for storage purposes.

This invention is usable with any supports such as tables, chairs, boards, benches, etc., of any nature, but it is disclosed herein as being applied to an ironing board merely for purposes of clarity of illustration.

Referring particularly to Figs. 1, 5 and 6, I have shown the board proper on which ironing operations

are performed at 10, a pair of primary or control legs 11 and 12, and a second pair of secondary or sliding legs 13 and 14. A bolt 15 serves as a common pivot for the legs and may be surrounded by front and back spacers 16 and 17, and an intermediate spacer 18, see Fig. 5. A bearing frame 20 is secured at 21 to the underside of board 10, see Fig. 4, and has pivoted thereto at 22 the upper ends of the primary legs.

Extending along the underside of board 10 is a guide bar or rail 25 spaced below the bottom of the board by washers or spacers 26 and held to the board by bolts or the like 27 which pass through the ends of the rail and the washers. The rail 25 extends through horizontal slots 28 in a cross bar 29 made preferably of sheet metal and bent down at its ends to form ears 30, see Fig. 2. The upper ends of the secondary legs are pivoted at 31 to the bent down ends or ears 30. The cross bar is in close contact with the underside of the board 10 and slides frictionally therealong when the height of the board is changed. As shown in Fig. 3 the top of the cross bar is formed as a flat strip 32 from the edges of which depend reinforcing flanges 33. It is in the latter that the aforesaid slots 28 are formed, and these flanges are on opposite sides of a vertical line passing through aligned pivots 31. In this way I insure smooth sliding of the cross bar along the rail while the bar contacts board 10. The rail is preferably metallic and is sufficiently resilient to flex upwardly under the weight of the board to effect the aforesaid frictional engagement.

The mechanism for adjusting the height of the board 10 is shown more particularly in Figs. 1, 6, 7 and 8. As shown in Figs. 1 and 6 the bottom

ends of the primary legs are connected together by a short bolt 35 from which the legs 11 and 12 diverge upwardly toward their pivots 22. A short distance above bolt 35 is a second somewhat longer bolt 36 which serves as a pivot for a pedal 37 and the left end of a bar 38 of channel form, see Fig. 8, and having upturned edges or flanges 39. The bar 38 may be made of metal and near that end of it adjacent to the secondary legs has secured thereto a housing 40 having front and back vertical walls 41 and 42 connecting with right and left end walls 43 and 44. Laterally extending feet 45 on the end walls are secured to the bottom of channel bar 38 at 46. The relation of the housing and bar 38 is shown in Figs. 7 and 8.

As seen in Fig. 6 the secondary legs are connected by a brace 50 to the center of which is secured an angle bearing 51. A lock rod 52 has one end thereof bent and extended through bearing 51 to have pivotal connection with the latter. Rod 52 extends away from brace 50 and passes through slide bearings or preferably closely fitting holes 53 and 54 in the right and left end walls 43 and 44, respectively, and projects some distance to the left of the housing 40, see Figs. 1, 6 and 7.

A second rod 55 is pivoted at 56 to the pedal above pivot bolt 36 and extends to the right and into housing 40, see Figs. 1 and 7, where it is bent laterally to form an eye 57 lying close to end wall 43 and surrounding rod 52. Between the eye 57 and the left end wall 44 are three movable members comprising a lock plate 60, a relatively strong compression spring 61 between eye 57 and plate 60, and a relatively weak spring 62 between the lock plate and the left end wall 44. A cylindrical stop 63 concentric with the lock rod 52 has a right hand stop surface 64 lying preferably in a plane perpendicular to rod 52 and positioned to engage the lock plate and hold it square across rod 52 when strong spring 61 is caused to exert considerable force on the lock plate. The latter has a hole 65 therein through which passes lock rod 52 and of a diameter slightly greater than that of rod 52. The lock plate has a broad lower edge 66 for engagement with the bar 38 as shown in Fig. 8, and a stop 67 secured to bar 38 may be used to limit motion of the lock plate 60 to the right, see Fig. 7.

As shown in Figs. 7 and 8, parts of the top 68 of the housing, rear wall 42, and left end wall 44 (Fig. 7) are removed to provide an opening 69 which permits entry of eye 57 on the control rod 55 into the housing. Opening 69 also facilitates assembly of the springs and lock plate on the lock rod 52 if the latter is inserted through the end wall 43 after the housing has been secured to the bar 38. The parts in the housing, however, can be assembled as indicated in Fig. 7, after which the housing can be secured to bar 38.

Assuming that the board is in the stable position shown in Fig. 1, weak spring 62 will be expanded to hold the lock plate 60 in the full line position shown in Fig. 7 in which position the bottom of the lock plate will be against stop 67 and weak spring 62 will hold the lock inclined. When the lock is thus placed the lower left edge of hole 65 frictionally engages the underside of the lock rod 52 and the latter together with bar 38 forms in effect a link of given length and holds the legs against spreading.

When it is desired to lower the board 10, the user will put her foot on pedal 37 and depress it, thereby rocking the pedal in a counter-clockwise

direction as viewed in Fig. 1 and moving control rod 55 to the left from the normal to the releasing position thereof. The eye 57 thereupon slides to the left along lock rod 52 and compresses strong spring 61, thereby overpowering the weak spring and moving the locking plate 60 to the dotted line position of Fig. 7 against the stop surface 64. The lock rod 52 is now unlocked and can slide through the lock plate, and by holding the left or adjacent end of the board 10 the user can lower the board to the desired level by movement in the direction of arrow *a*, Fig. 9, after which the pedal is released and the parts return to the locking position shown in Fig. 7, full lines. The board 10 will now remain in its new position shown in dot and dash lines, Fig. 9.

During lowering of the board 10 the bar or head 29 will slide frictionally along the rail 25 to resist too rapid a descent of the board if the user should not have a firm hold on it. Also, the legs 13 and 14 slide along the floor and thus supply additional friction resisting downward movement of the board. The latter, however, will ordinarily be heavy enough to move down when the pedal is lowered and overcome the frictional resistances mentioned.

When the board is to be raised the user places her foot on the bottoms of the control legs near the bolt 35, and then raises the board as indicated by arrow *b*, to the dotted position of Fig. 10. During this operation the lock rod slides to the left, Fig. 7, through the lock plate without requiring release of the lock. The lock plate will prevent reverse motion of the lock rod to the left, and the board will remain in its raised position. Raising of the board may be easier if the user places her foot on the lower ends of the control legs and then depresses the pedal, since this procedure will move the lock plate to unlocking position and the lock rod can slide through it easily.

Fig. 11 shows the board collapsed and standing on end for storage purposes. When the board is to be put away the pedal will be depressed until the board falls to a position close to the floor, after which it can be stood on end as shown in Fig. 11. In the collapsed position the housing engages the pivot bolt 15 and thus prevents bending of the control and lock rods if excessive pressure should be accidentally exerted on the board. The lock rod is long enough to permit this collapsing.

From the foregoing it will be seen that I have provided an ironing board with pairs of legs pivoted together and connected in pairs by a link variable as to length for the purpose of adjusting the height of the board. The link extends between the lower ends of the legs and preferably does not project beyond them, hence there is no danger that the user will trip over it, or the pedal by which the lock is released. The board can be folded and stored as suggested in Fig. 11. When the board is folded the housing will prevent the pivot bolt 15 from engaging and bending the control and lock rods. The board can be raised to a higher adjusted position merely by lifting the board, due to the fact that the lock will slip or slide in a direction to permit such an adjustment. When the board is to be lowered the lock is released, either by foot or by hand, after which the board will fall of its own weight to the desired height, and the lock will return automatically to holding position upon release of the control means.

Having thus described my invention it will be

seen that changes and modifications may be made therein by those skilled in the art without departing from the spirit and scope of the invention and I do not wish to be limited to the details herein disclosed, but what I claim is:

1. Adjustable supporting means comprising, crossed pairs of legs pivoted together two members slidably connected to each other and located below the point of crossing of said pairs of legs, one member operatively connected to one of said pairs of legs and the other member operatively connected to the other pair of legs, lock means normally locking said members together to prevent separation of the lower ends of said pairs of legs, a pedal pivotally mounted with respect to one of said pairs of legs, and connections between said pedal and lock means effective when the pedal is depressed to move said lock to abnormal position to unlock said members and permit relative sliding movement of the latter in a direction corresponding to separation of the lower ends of said pairs of legs.

2. Adjustable supporting means for a board or the like, cross pairs of legs pivoted together and supporting the board at their upper ends, the board due to the weight thereof tending to separate the lower ends of said pairs of legs, a lock rod member operatively connected to the lower end of one of said pairs of legs, a holding bar member operatively connected to the lower ends of the other pair of legs and having a sliding connection with the lock rod member, a lock mounted on one of said members normally locking said member against motion in a direction corresponding to separation of the lower ends of said pairs of legs, a pedal movably supported by the lower ends of one of said pairs of legs, and a control rod connected to said pedal and guided and supported by one of said members and effective when the pedal is depressed to cause said lock to unlock said lock rod, whereupon said lock rod is capable of sliding movement with respect to said housing means in a direction corresponding to separation of the lower ends of said pairs of legs.

3. In adjustable supporting means for a member, cross pairs of legs pivoted together and supporting the member at their upper ends, the member due to the weight thereof tending to separate the lower ends of said pairs of legs, a holding bar, a pivotal connection between said bar and the lower ends of one of said pairs of legs, a pedal pivotally mounted on said pivotal connection, a lock rod operatively connected to the lower ends of the other pair of legs, lock means normally in position to lock the holding bar and lock rod together to prevent relative movement thereof in a direction corresponding to separation of the lower ends of the pairs of legs, and a control rod for the lock operatively connected to the pedal and effective when the latter is depressed to cause said lock to move to unlocked position, thereby enabling the lock rod to move relatively to the holding bar in a direction corresponding to separation of the lower ends of said pairs of legs.

4. Adjustable supporting means comprising, crossed pairs of legs pivoted together two members slidably connected to each other and located below the point of crossing of said pairs of legs, one member operatively connected to one of said pairs of legs and the other member operatively connected to the other pair of legs, adjacent ends of said members mutually supporting each other, lock means operatively secured

to one member for engagement with the other member, resilient means normally holding the lock means in position to lock the members together to prevent separation of the lower ends of said pairs of legs, and pedal means held in normal position by said resilient means and operative when moved to releasing position to move said lock means against the action of said resilient means to abnormal position to unlock said members, the latter thereupon being capable of relative sliding movement to permit separation of the lower ends of said pairs of legs, the resilient means returning the lock means to normal position to lock said members together upon movement of the pedal means to the normal position thereof.

5. In adjustable supporting means for a member, crossed pairs of legs pivoted together and supporting the member at their upper ends, the member due to the weight thereof tending to separate the lower ends of said pairs of legs, holding bar means operatively connected to the lower ends of one of said pairs of legs, a lock rod operatively connected to the lower ends of the other pair of legs and having sliding relation with respect to the holding bar means, a lock operatively secured to said holding bar means surrounding the lock rod, a spring normally holding the lock in locked relation with respect to the lock rod, a second spring stronger than the first named spring normally ineffective to move the lock to unlocked position, and pedal operated control means extending into operative relationship with respect to said second spring and effective when moved in a given direction to cause said second spring to overpower the first named spring and move the lock to unlocked relation with respect to said lock rod, whereupon said lock rod is capable of movement relatively to the holding bar means in a direction corresponding to separation of the lower ends of said pairs of legs.

6. A continuously adjustable supporting device comprising crossed pairs of legs pivoted together, a rod connected to each of said leg pairs, a tilting friction lock means on one rod means to normally tilt the lock means to grip the other rod to prevent relative separating motion thereof so that the leg pairs cannot separate, said lock means being effective to provide for easy, smooth, and continuous relative advance of the rods to allow the leg pairs to move toward each other, and means to release the lock means.

7. A continuously adjustable supporting device comprising crossed pairs of legs pivoted together, a rod connected to each of said leg pairs, a lock means on the rods and being effective normally to prevent relative separating motion thereof so that the leg pairs cannot separate, said lock means being effective to provide for easy, smooth and continuous relative advance of the rods to allow the leg pairs to move toward each other, means to release the lock means, means to normally urge the lock means to locking position, a control means to operate the lock release means remotely from the lock means, one of the rods being a lock rod and the lock means comprising a plate having an opening through which the lock rod extends, means normally tilting the plate to grip the lock rod against relative motion in one direction, and the control means being adapted to overcome the plate tilting means to release the lock rod at will.
